10 Claims. (Cl. 221—4)

This invention relates to cup dispensers for paper drinking cups and the like which are dispensed one at a time from a nested stack, and more particularly to improvements in a dispenser of the type which is adjustable to accommodate cups of various sizes.

Paper and plastic drinking cups are becoming increasingly popular in the home, in restaurants, and even in public conveyances. Cups of various sizes and configurations are available today for serving a variety of comestibles, and these are ordinarily packaged by the manufacturers in nested stacks which may be placed in a suitable cabinet or magazine from which the cups may be removed one at a time. The dispenser cabinet is a separately manufactured and rather costly accessory, and it is recognized that an adjustable dispenser rather than a separate dispenser for the many sizes of cups in use is desirable. There are available in the prior art several adjustable cup dispensers which attempt to satisfy this requirement. These have been found generally unsatisfactory either because they involved complex mechanisms and are costly to manufacture or do not always ensure that only a single cup will be withdrawn each time from the nested stack and with the slightest pull.

The principal object of the present invention, therefore, is to provide an improved cup dispenser of simple construction which is readily and conveniently adjustable to accommodate various size cups.

Another object of this invention is to provide a cup dispenser having improved adjustable means for supporting cups of various sizes in a proper manner to enable easy and dependable extraction of the cups one at a time.

Another object of this invention is to provide an improved cup dispenser having selectively adjustable supporting means capable of accommodating nested cups of various sizes and of providing easy and dependable extraction of cups singly therefrom irrespective of the size of the cups.

A further object of this invention is to provide an improved cup dispenser of simple and durable construction, which is attractive in appearance, inexpensive to manufacture, and may be conveniently installed for wall or counter use in either gravity or force feed disposition.

Numerous other objects and advantages of the invention will be apparent as it is better understood from the following description, which, taken in connection with the accompanying drawings, discloses a preferred embodiment thereof.

In carrying out these objects, there is provided a dispenser comprising a tubular magazine having a discharge opening in an end thereof, a plurality of spring fingers secured in the magazine in spaced circumferential relation and forming at their free ends cup-engaging jaws, and a rotatable selector member concentrically mounted to the discharge end of the magazine and having arcuate cam segments correspondingly spaced with respect to and forcibly engaging the spring fingers for selectively positioning the jaws in the discharge opening to the accommodation of cups of differing sizes.

Referring to the drawings:

FIGURE 1 is a perspective view of the preferred form of the present invention;

FIG. 2 is a sectional view taken substantially along line 2—2 of FIG. 1;

FIG. 3 is a sectional view taken substantially along line 3—3 of FIG. 2;

FIG. 4 is a sectional view taken substantially along line 4—4 of FIG. 3;

FIG. 5 is a sectional view taken substantially along line 5—5 of FIG. 3;

FIG. 6 is a sectional view taken substantially along line 6—6 of FIG. 4;

FIG. 7 is a sectional view similar to FIG. 4, showing the operative parts of the invention in a different position of adjustment;

FIG. 8 is a fragmentary sectional view illustrating an alternate embodiment of the invention; and

FIG. 9 is a partial elevational view showing the invention adapted for cup dispensing in inverted fashion.

As a preferred or exemplary form of the invention, FIG. 1 illustrates a dispenser comprising a tubular barrel or magazine 10 having a removable top closure 11 and a selector ring assembly generally designated 12 concentrically mounted to the magazine at its discharge end. A nested stack S of cups, which may be one of many types and sizes now available on the market for serving a variety of comestibles, is placed within the dispenser so that the terminal cup 13 in the stack projects in a bottom-foremost manner from the discharge end. A sight opening or window 14 may be provided in the wall of the magazine near its discharge end in order to ascertain when the supply of cups in the dispenser is near exhaustion and replenishment required.

As shown, the dispenser may be provided with a bracket 15 and mounted to a suitable pedestal 16 for counter top use, although it is equally suited for wall use when suspended on a suitable hanger or bracket (not shown). Discharge may be from the bottom of the dispenser, in which case the terminal cup 13 is presented in accessible position by gravity feed. Alternately, the dispenser may be inverted for cup extraction from the top, in which case the stack S is maintained in accessible position by a biased follower acting within the magazine (see FIG. 9).

The operative features of the interior supporting means and the selector ring assembly 12 are best shown in FIG. 3. The supporting means comprises a plurality of spring fingers 17, preferably of spring steel, which are mounted in circumferentially spaced relation about the interior wall of magazine 10. Any number of these fingers may be used, but an arrangement found to give excellent supporting control with consistently easy and dependable cup extraction has been four equally spaced fingers providing a 4-point supporting structure. As shown, the fingers 17 are mounted longitudinally of magazine 10 and are secured thereto at a point remote from the discharge end of the dispenser. The fingers may be anchored in the magazine by rivets or other suitable means of attachment, but where the magazine 10 is of easily formable material, such as extruded plastic tubing, it is preferred to anchor the fingers in dovetail grooved tracks 18 formed in the magazine wall.

The free end of each finger 17 is formed in the shape of a cup-engaging jaw generally designated 19. Drinking cups of the type herein contemplated ordinarily are of a conical or frustoconical configuration and are formed with beaded or curled reinforcing lips at their open ends. Jaws 19 are appropriately formed to provide a shoulder 20 on each finger which engages below the lip of the terminal cup 13 to retain the entire stack S. Extending from shoulder 20 is a short outwardly tapered portion 21 which is bent abruptly outwardly near the very end of the finger to provide a radially projecting control arm 22. The purpose of this rather unique construction of spring fingers 17 and their supporting jaws 19 will be

more fully explained hereinafter in cooperative relation with the selector ring assembly 12, now to be described.

Selector ring assembly 12 provides the actuating means for varying the radial positions of cup-engaging jaws 19 within the discharge opening of magazine 10 to the accommodation of cups of various diameters. The main element of the assembly is a selector ring 23 having inwardly projecting cam segments 24 (FIG. 4) corresponding in number to spring fingers 17 and being equally spaced about the ring 23. The outer edge 25 of ring 23 is contoured to provide a convenient finger grip surface for manual rotation. As best shown in FIG. 4, illustrating jaws 19 in their fully contracted position, cam segments 24 have inner arcuate faces 26 against which the control arms 22 at the terminal or free ends of fingers 17 forcibly engage so that rotative movement of ring 23 is transmitted into radial movement of arms 22 to selectively position jaws 19 within the magazine. The point of engagement of arm 22 against cam face 26 is identical for all four fingers so that rotation of ring 23 will effect an equal radial translation of all of the jaws 19 between a maximum and minimum setting corresponding to the geometric shape of the cam segments 24. An interim selector setting is illustrated in FIG. 7, showing jaws 19 almost fully retracted to accommodate a larger size cup.

Selector ring 23 is rotatably mounted to magazine 10 between an upper adapter ring 27 and lower adapter ring 28, which together form a bearing race for the selector ring. Preferably, rings 27 and 28 are of identical and interchangeable construction and may be formed from any material capable of dimensional stability, such as moldable resinous plastic. These two rings are secured against rotation to magazine 10 by means of equally spaced raised projections or splines 29 formed on the inner face of each ring which fit within slots 30 cut in the discharge end of the magazine. These slots are circumferentially aligned with fingers 17 and are sufficiently wide to permit control arms 22 to pass therethrough to engage cam faces 26. As can be seen in FIG. 3, the dimensional stack of the several component parts in the selector ring assembly is such that adapter rings 27 and 28 provide a rather snug-fitting bearing race for selector ring 23 but yet do not frictionally bind the selector ring or make interfering contact with control arms 22. The entire assembly is held together and locked to magazine 10 by any convenient means of attachment, an example being a resilient lock spring 31 of semi-circular configuration having end cleats 32 which extend through diametrically opposed holes 33 in the magazine wall and into holes 34 bored into the lower adapter ring 28 in alignment with holes 33 (see FIG. 5). Spring 31 is also provided with a pair of spaced raised projections 35 which snap into spaced depressions 36 in the inner surface of lower adapter ring 28 to secure the spring in a hidden position within the end of the magazine.

Preferably, splines 29 on each adapter ring are provided with opposed lips 37 inwardly of cam segments 24 and which are cut out to define narrow slots 38 through which control arms 22 will pass. In this case, mounting slots 30 in magazine 10 are slightly wider than arms 22 so that lips 37 will make abutting engagement to each side of control arms 22, thereby keeping these control arms properly engaged on their respective cam surfaces 26 as well as maintaining the other conforming surfaces of rings 27 and 28 frictionally free from selector ring 23.

It will be seen from the arrangement just described that the terminal cup 13 in the stack S is held in the jaws 19 on shoulders 20 at a point intermediate the two ends of spring fingers 17. The forcible engagement of radial control arm 22 against cam face 26 flexes each finger inwardly about its anchor point in track 18 so that the finger is flexible between two points of support at its terminal ends. Preferably, the fingers are made long enough and their anchor points are sufficiently

remote from jaws 19 so that the reactance pressure of the fingers will vary only slightly irrespective of the radial setting of the jaws. In this manner, the jaws 19 are capable of exerting a longitudinal holding force against the stack of cups bearing on shoulders 20, and yet a slight tug or pull on the terminal cup 13 will expand or bow the fingers radially outwardly between their terminal support points sufficiently to free this cup from the jaws. The next succeeding cup is caught on shoulders 20 as stack S shifts vertically in the magazine, the spring fingers instantly snapping back with sufficient pressure to positively support the load. Thus, there is provided a simple yet foolproof supporting jaw arrangement for ensuring easy and dependable cup extraction one at a time from the magazine regardless of the size of the cups.

Depending on the number of spring fingers 17 to be used and the geometry of the corresponding cam segments 24, the amount of rotation of selector ring 23 to accomplish the entire range of possible settings will vary. That is, a half turn or substantially 180° rotation of the selector ring could be utilized, if desired, with a 2-point supporting arrangement to effect full radial translation of jaws 19 through a range of settings. Obviously, the permissible amount of rotation of selector ring 23 to effect the full range of possible settings is a fraction equal to the reciprocal of the number of spring fingers 17 used in any specific arrangement. In the preferred 4-point embodiment herein described, this is a quarter turn or, to be more exact, slightly less than a quadrant when allowing for the width of control arms 22. To control the limits of this movement, either of the adapter rings 27 or 28 may be provided with interrupted grooves 39 (FIG. 5) facing and overlying the operative path of the four cam segments 24. Each cam segment in turn is provided at its terminal end with a stop lug 40 which rides in the corresponding groove 39 and is engageable against the end walls of the groove to limit rotation of selector ring 23. The arcuate length of each groove 39 is sufficient to permit its associated lug 40 to move slightly less than a full quadrant. It will be understood that one groove and cooperating lug will suffice to define the limits of selector ring rotation; however, it is preferred to use a lug and groove in each quadrant to enable the parts to be easily assembled without regard to alignment and to ensure that excessive twisting by a careless user would not break or damage the unit.

To facilitate the accurate selection of a desired setting, the outer edge 25 of selector ring 23 may be provided with spaced markings or indicia 41 corresponding to cups of various predetermined sizes. Visual alignment of any one of these marks with a fixed registering mark 42 placed on magazine 10 or one of adapter rings 27 or 28 provides a convenient dial selection of the desired cup size setting.

Once a setting has been made, the pressure of spring fingers 17 acting against cam segments 24 would normally hold selector ring 23 at this setting against any tendency to shift due to the slight vibration occasioned by repeated extraction of cups. However, the contacting edges of control arms 22 are preferably rounded so that frictional contact with cam faces 26 is at a minimum, and, accordingly, additional means are required to secure the setting once made. As shown in FIG. 6, this may take the form of a spring keeper element 43 mounted in a recess 44 in one of the adapter rings 27 or 28 and having a pair of projecting ratchet prongs 45 which engage in ratchet track serrations 46 formed in the opposing face of a corresponding cam segment 24. In most positions of the selector ring, keeper element 43 extends over two adjacent cam segments so that prongs 45 make locking engagement with these two segments at the same time. If desired, all four cam segments may be similarly serrated so that regardless of the angular position of the selector ring 23 when the parts are initially

assembled, keeper element 43 will be properly engaged with one or more of the serrated cam segments.

Although adapter rings 27 and 28 have been described hereinbefore as interchangeable, it will be understood that the structural relationship of the cooperating parts of selector ring assembly 12 in each quadrant is such that when keeper element 43 is mounted in the lower ring for engagement against serrations 46 in the bottom surface of the cam segments 24, then stop lugs 40 necessarily will be located on the upper surface of the cam segments and the cooperating grooves 39 for these lugs will be located in the upper adapter ring.

Alternately, the cam faces 26 themselves may be knurled or serrated, as shown at 46' in FIG. 8, and the contacting ends of control arms 22 may be formed into rounded points 47 to effect a ratchet-like locking action. This latter arrangement has the advantage of eliminating the keeper element 43, but obviously requires greater dimensional control in the forming of each cam segment to ensure that the radial position of each finger 17 acting thereagainst is identical for each and every circumferential position on the corresponding cam surfaces.

FIG. 9 illustrates the instant invention adapted for cup dispensing from the top end of the dispenser. Although it may be mounted in this position on either a wall bracket or supporting pedestal as hereinbefore suggested, the illustrated arrangement shows the dispenser inverted and recessed within a well in a counter top with only the selector ring assembly 12 in view. A collar 48 bolted or otherwise attached to the counter top is provided surrounding the magazine 10 inwardly of the selector ring assembly for supporting the dispenser in this position. A follower 49 acting against the inner terminal cup in stack S under the influence of a coil spring 50 is the conventional arrangement for maintaining the outer terminal cup in accessible position.

It is thought that the invention and many of its attendant advantages will be understood from the foregoing description and it will be apparent that various changes may be made in the form, construction, and arrangement of the parts without departing from the spirit and scope of the invention or sacrificing all of its material advantages, the form hereinbefore described being merely a preferred embodiment thereof.

We claim:

1. A cup dispenser for accommodating cups of various diameters to be dispensed individually from a nested stack, comprising a magazine having a discharge opening in one end thereof, a plurality of circumferentially spaced spring fingers having one end fixed within said magazine with said fingers extending longitudinally toward the discharge opening, said fingers being deformed inwardly toward the center of the magazine adjacent said discharge end to define cup-engaging jaws adapted to support the terminal cup in said stack, said cup-engaging jaws terminating in outwardly extending radial control arms formed by the ends of said fingers and an adjustable member mounted on said magazine at said discharge opening, said member having inwardly projecting cam surfaces which forcibly engage against said control arms and coat therewith upon selective adjustment of said member to control the operative position of said jaws within said magazine to thus selectively permit said jaws to accommodate cups of varying diameters.

2. The dispenser of claim 1 wherein said adjustable member is a selector ring for progressively varying the diameter of said jaws in response to selective rotation of said ring.

3. The dispenser of claim 2 wherein at least one of said cam segments is provided with a projection adjacent its terminal end engageable with stop elements fixed to said magazine to confine rotation of said selector ring within predetermined limits.

4. The dispenser of claim 2 wherein said selector ring is provided with serrations along one of its surfaces engageable with a yieldable keeper element fixed to said magazine to frictionally secure said selector ring in a select position.

5. The dispenser of claim 2 wherein said cam surfaces are arcuate and knurled along their length and have outwardly projecting portions which are constructed to yieldably engage said knurled surfaces to frictionally secure said selector ring in a select position.

6. A cup dispenser for accommodating cups of various sizes to be dispensed individually from a nested stack, comprising a tubular magazine having a discharge opening in one end thereof, a plurality of spring fingers mounted in said magazine in equally spaced circumferential relation, said fingers extending longitudinally from anchor points remote from said end and being formed at their free ends into cup-engaging jaws, said jaws having a shoulder contoured to engage under the lip of the terminal cup in said stack and a terminal portion extending radially outwardly of said shoulder, a housing member fixed in circumferentially spaced slots at the discharge end of said magazine and providing a peripheral annular bearing surrounding said magazine, the position of said slots substantially corresponding to the circumferential spacing of said fingers for receiving the terminal portion on each of said jaws, and a selector ring rotatably held in said annular bearing having inwardly projecting arcuate cam segments corresponding to said terminal portions and forcibly engaging thereagainst through said slots, said cam segments being adapted upon rotation of said ring to flex said fingers radially inwardly about their anchor points to move said jaws into operating position corresponding to the support of cups of differing lateral dimensions.

7. The dispenser of claim 6 wherein said selector ring is provided with indicia corresponding to differing cup sizes of predetermined lateral dimensions.

8. The dispenser of claim 6 wherein a biased follower element is provided internally of said magazine to act against said stack opposite said discharge opening and maintain said terminal cup in accessible position.

9. The dispenser of claim 6 wherein said cup-engaging jaws comprise a sharply inturned portion defining said shoulder and an outwardly tapering portion extending longitudinally from said shoulder and connecting with said terminal portion.

10. The dispenser of claim 6 wherein said housing is provided with circumferentially spaced surfaces defining limits of rotation of said selector ring and at least one of said cam segments is provided with a projection adjacent its terminal end engageable with said surfaces to limit rotation of said ring between a maximum and minimum select setting.
